UNITED STATES PATENT OFFICE

CALVERT B. COTTRELL, 3D, OF WESTERLY, RHODE ISLAND, ASSIGNOR TO C. B. COTTRELL & SONS COMPANY, OF WESTERLY, RHODE ISLAND, A CORPORATION OF DELAWARE

BED AND CYLINDER PRINTING PRESS

Application filed June 5, 1928. Serial No. 282,998.

My invention consists in a six revolution bed and cylinder two color printing press in which a single impression cylinder of comparatively small size is caused to retain the sheet thereon for both printings, thereby ensuring perfect register and obviating the necessity of transferring the sheet after its first printing on one impression cylinder to another impression cylinder for its second printing.

My invention further consists in a printing press of this character in which the single impression cylinder is arranged to make six revolutions during a complete reciprocation of the bed; the impression cylinder making three revolutions in one direction on the forward or printing stroke of the bed and three revolutions in the opposite direction on the return or non-printing stroke of the bed; the sheet being printed twice and then transferred to the delivery mechanism during the three revolutions of the impression cylinder in one direction and then conveyed to and deposited on the delivery table during the three revolutions of the cylinder in the opposite direction.

The object of my invention is to not only ensure more perfect printing register but also to materially reduce the weight and cost of the printing press and also to bring the feed and delivery mechanisms down into convenient position for the operator.

A motive fluid means is shown for reciprocating the form bed, such means forming the subject matter of my copending application filed of even date herewith, its serial number being 282,997.

A practical embodiment of my invention is represented in the accompanying drawings, in which—

Fig. 1 represents the printing press in side elevation with the parts in the positions they assume when the form bed is about to start on its forward or printing stroke, the impression cylinder is about to take a sheet from the feed board and a twice printed sheet is being deposited on to the delivery table by the conveying means of the delivery mechanism.

Fig. 2 represents an enlarged detail side

view of the impression cylinder and its adjacent parts, showing more clearly the several devices operated by the bed for controlling the feeding and delivery of the sheets, the parts being in the positions shown in Fig. 1.

Fig. 3 represents a detail cross section taken in the planes of the line III—III of Fig. 2, looking in the direction of the arrows.

Fig. 4 represents a detail longitudinal section taken in the plane of the line IV—IV of Fig. 3, looking in the direction of the arrows with the parts in the positions they assume when the leading edge of the twice printed sheet is being transferred from the impression cylinder to the guides of the delivery mechanism.

The main frame of the printing press is denoted by 1, the reciprocating form bed by 2, the two forms thereon, by 3 and 4 and the two form inking mechanisms by 5 and 6.

The sheet feed table of any well known or approved sheet feeding mechanism is denoted by 7 and its feed guide by 8. The single impression cylinder is denoted by 9 and its sheet grippers by 10. The sheet delivery mechanism may be of any well known or approved form and it is shown herein as comprising a delivery table 11, a reciprocating conveying means 12 and the guides 13, 14 for directing the twice printed sheets from the impression cylinder to the reciprocating conveying means.

The motive fluid means for reciprocating the form bed is denoted generally by 15 and will not be specifically described herein as it forms the subject matter of my copending application hereinbefore referred to.

The impression cylinder 9, the circumference of which is substantially one-third the stroke of the bed 2 is geared at all times to the bed through the usual rack and pinion connection 16, 17. This impression cylinder 9 is raised in the usual manner bodily out of contact with the forms without disconnecting the cylinder from the bed, during the return or non-printing stroke of the bed, by well known or approved means denoted generally by 18.

The several devices for controlling the passage of the sheet to and from the impression cylinder will be described generally but not in detail, as they may be of any well known or approved construction.

5 In the present instance the bed is provided on one side thereof with a feed guide operating cam 19 arranged in position to engage the stud or roller 20 on the lower end of the bar 21, the upper end of which is connected to the rock lever 22 which controls the operation of the feed guide 8 to release the sheet as the cylinder is about to start on its first revolution.

15 On the same side of the form bed and adjacent to the feed guide operating cam 19 there is located the cam 23 which is arranged in position to engage a stud or roller 24 carried by the lateral sliding pin 25 connected to the lever 26 which controls the operation of the tumbler cam pin 27 to bring it into and out of engagement with the gripper tumbler cam 28 for operating the grippers 10 at the proper time to receive and grasp the head end 25 of the sheet fed from the feed table as the impression cylinder is about to start on its first revolution.

The form bed is also provided on its opposite side with a gripper release cam 29 arranged to engage a stud or roller 30 carried by a rod 31 connected to one arm 32 of a rock lever, the other arm 33 of which is provided with a cam 34 arranged in position to engage a stud or roller 35 on an arm 36 carried by the impression cylinder gripper shaft. This cam 29 is so located that the impression cylinder grippers 10 will be released as the impression cylinder starts on its third revolution, for permitting the transfer of the head end of the sheet to the delivery mechanism as the sheet is receiving its second printing.

To ensure the transfer of the head end of the sheet to the guides 13, 14 of the delivery mechanism I also provide the form bed with 45 a stripping finger operating cam 37, arranged in position to engage a stud or roller 38 on a rod 39 connected to a lever 40 carrying a cam 41 arranged to be brought into engagement with a stud or roller 42 carried by an arm 43 of the stripper shaft 44 so as to raise the stripper fingers 45 at the proper time to direct the leading edge of the sheet between the said guides 13, 14.

The form bed is also provided on one side 55 with a cam 46 arranged in position to engage the studs or rollers 47, 48 to raise the form rollers of the inking mechanism 5 so that they will not come in contact with the form 4. The bed is also provided on the other side 60 with a cam 49 arranged to engage the studs or rollers 50, 51 and 52 to raise the form rollers of the inking mechanism 6 so that they will not come in contact with the form 8. The mechanism for automatically controlling 65 the operation of the inking mechanisms 5 and

6 at the proper times may be of any well known or approved construction.

To ensure the positive feed of the sheet from the impression cylinder to the delivery mechanism I provide coacting rollers 53, 54, 70 adjacent the guides 13, 14 and I also provide rollers 55 arranged to be brought into engagement with the sheet while on the impression cylinder, said rollers 55 being carried by one arm 56 of a rock lever, the other arm 57 of which is connected by a rod 58 to one arm 59 of another rock lever, said last named rock lever having an arm 60 carrying a stud or roller 61 arranged to be engaged by a cam 62 carried by a gear 63 which meshes with a gear 64 fast on the impression cylinder shaft 65 exterior to the frame 1.

It will be seen from the above description that I have provided a bed and cylinder printing press in which the necessity of transferring the sheet between its first and second printings is obviated. I have also been able to provide a relatively small impression cylinder, thereby materially reducing the weight and expense of the press and also bringing 90 the feed and delivery mechanisms down into a more accessible position for the operator.

It is evident that various changes may be resorted to in the construction, form and arrangement of the several parts without departing from the spirit and scope of my invention, hence I do not intend to be limited to the particular embodiment herein shown and described, but

What I claim is:—

1. In a bed and cylinder two color printing press, a reciprocating bed and a single impression cylinder, said cylinder being arranged to make three revolutions in one direction during the printing stroke of the bed 105 and three revolutions in the opposite direction during the non-printing stroke of the bed.

2. In a bed and cylinder two color printing press, a delivery mechanism, a reciprocating bed and a single impression cylinder, said cylinder being arranged to make three revolutions in one direction during the printing stroke of the bed and three revolutions in the opposite direction during the non-printing stroke of the bed, the sheet being taken 110 printed twice and transferred to the delivery mechanism during the first three revolutions of the cylinder.

3. In a bed and cylinder two color printing 120 press, a delivery mechanism, a reciprocating bed and a single impression cylinder, said cylinder being arranged to make three revolutions in one direction during the printing stroke of the bed and three revolutions in the opposite direction during the non-printing stroke of the bed, the sheet being taken, 125 printed twice and transferred to the delivery mechanism during the first three revolutions of the cylinder, and mechanism operable to 130

release the leading end of the printed sheet at the beginning of the third revolution of the cylinder, to permit its transfer to the delivery mechanism.

4. In a bed and cylinder two color printing press, a reciprocating bed, a single impression cylinder and a delivery mechanism including a delivery table and means for conveying the printed sheet thereto from the impression cylinder, said cylinder being arranged to make three revolutions in one direction during the printing stroke of the bed and three revolutions in the opposite direction during the non-printing stroke of the bed, the sheet being taken, printed twice and transferred to the printed sheet conveying means of the delivery mechanism during the first three revolutions of the cylinder and conveyed to and deposited on the delivery table during the last three revolutions of the cylinder.

5. In a bed and cylinder two color printing press, a reciprocating bed, a single impression cylinder and a delivery mechanism including a delivery table and means for conveying the printed sheet thereto from the impression cylinder, said cylinder being arranged to make three revolutions in one direction during the printing stroke of the bed and three revolutions in the opposite direction during the non-printing stroke of the bed, the sheet being taken, printed twice and transferred to the printed sheet conveying means of the delivery mechanism during the first three revolutions of the cylinder and conveyed to and deposited on the delivery table during the last three revolutions of the cylinder, and mechanism operable to release the leading end of the printed sheet at the beginning of the third revolution of the cylinder, to permit its transfer to the printed sheet conveying means of the delivery mechanism while the sheet is still receiving its second printing.

6. In a bed and cylinder two color printing press, a reciprocating bed and a single impression cylinder, the circumference of the impression cylinder being substantially one-third the stroke of the bed.

7. In a bed and cylinder two color printing press, a reciprocating bed and a single impression cylinder, said cylinder being arranged to make three revolutions in one direction during the printing stroke of the bed and three revolutions in the opposite direction during the non-printing stroke of the bed, grippers on the cylinder and cams positioned on the bed for operating the grippers to cause them to receive and grasp the sheet as the cylinder starts its first revolution and to release the sheet as the cylinder finishes its second revolution.

8. In a bed and cylinder two color printing press, a delivery mechanism, a reciprocating bed and a single impression cylinder, said

cylinder being arranged to make three revolutions in one direction during the printing stroke of the bed and three revolutions in the opposite direction during the non-printing stroke of the bed, the sheet being taken, 70 printed twice and transferred to the delivery mechanism during the first three revolutions of the cylinder, grippers on the cylinder and cams positioned on the bed for operating the grippers to cause them to receive and grasp 75 the sheet as the cylinder starts its first revolution and to release the sheet as the cylinder finishes its second revolution.

In testimony, that I claim the foregoing as my invention, I have signed my name this 80 first day of June A. D. 1928.
